UNITED STATES PATENT OFFICE.

WILLIAM W. STEVENS, OF PORTLAND, MAINE, ASSIGNOR TO NATHANIEL P. RICHARDSON & CO., OF SAME PLACE.

IMPROVEMENT IN COAL-SIFTERS.

Specification forming part of Letters Patent No. **40,449**, dated October 27, 1863.

To all whom it may concern:

Be it known that I, WILLIAM W. STEVENS, of the city of Portland, county of Cumberland, and State of Maine, have invented an Improvement in Coal-Sifters for the purpose of sifting ashes from coal; and I do hereby declare that the following is a full and exact description of the same, reference being had to the accompanying drawings, and the letters and figures of reference thereon.

Of the said representation, Figure 1 represents the cover of the sifter. Fig. 2 represents the body of the sifter. Fig. 3 represents the ring used on the top of any round body. Fig. 4 represents the sifter as it appears when placed on the top of a barrel and ready for use.

I do not claim a patent on any part of the sifter, nor on the reciprocating rotary or the

rocking motion distinct of themselves, as they have been patented before.

What I do claim as my invention, and desire to secure by Letters Patent, is—

The combination of the two motions, reciprocating rotary and rocking motion, as applied to a coal-sifter, the first motion being obtained by moving the handles A A from left to right or right to left, the second motion by turning the handles A A up and down, giving the rocking motion.

In testimony whereof I have hereunto set my hand and seal this the 16th day of April, A. D. 1863.

WILLIAM W. STEVENS. [L. S.]
